[57] CLAIM

The ornamental design for an optical gun sight mount, as shown and described.

DESCRIPTION

FIG. 1 is a perspective view of the optical gun sight mount;

FIG. 2 is a rear elevational view;

FIG. 3 is a front elevational view;

FIG. 4 is a left side elevational view;

FIG. 5 is a top elevational view;

FIG. 6 is a right side view; and

FIG. 7 is a bottom plan view.

The broken lines in FIG. 6 are not part of the design of the article sought to be patented, but show the manner in which an optical gun sight is carried by the mount of this invention and the manner in which the mount is carried by a firearm receiver.
